(57) **CLAIM**

The ornamental design for the vehicle tail sign, as shown and described.

DESCRIPTION

FIG. 1 is a front perspective view of a vehicle tail sign, mounted to the tailgate of a pickup truck, showing my new design;

FIG. 2 is a front view thereof;

FIG. 3 is a top side view thereof;

FIG. 4 is a back view thereof; and,

FIG. 5 is a side view thereof.

The broken lines in FIG. 1, showing a portion of the back of a pickup truck on which the vehicle tail sign is mounted, are for the purpose of illustrating environmental structure and form no part of the claimed design.
